CARRYING CASE FOR BOWLING BALL AND SHOES

Thomas L. Telford, 1024 E. 5th St., Royal Oak, Mich.

Filed Nov. 20, 1961, Ser. No. 67,607

Term of patent 14 years

(Cl. D87—5)

FIG. 2

FIG. 1 is a side elevational view of a carrying case for bowling ball and shoes showing my new design.

FIG. 2 is an end elevational view thereof.

FIG. 3 is a top plan view thereof.

FIG. 4 is an end elevational view thereof in the open position.

FIG. 5 is an enlarged perspective view thereof in the open position; and

FIG. 6 is an enlarged top plan view thereof in the open position.

The essential features of my design are shown in full lines particularly the internal compartments shown in FIGS. 5 and 6 wherein the bottom portion of the case contains a central bowling ball receptacle having cylindrical side walls and a hemi-spherical bottom wall and end pockets at either end of the ball receptacle, and wherein each of the top portions of the case contain a divider member having a partial spherical conformation

together constituting a hemi-spherical top wall for the bowling ball receptacle with each divider members and top portions of the case forming a shoe receptacle and with said dividers farther constituting top covers for the end pockets in the bottom portion of the case. The bowling ball and shoes shown in dotted lines in FIG. 6 are for illustrative purposes only.

I claim:

The ornamental design for a carrying case for bowling ball and shoes, as shown and described.
